UNITED STATES PATENT OFFICE

ROLAND J. OLANDER, OF CHICAGO, ILLINOIS, ASSIGNOR TO W. H. MINER, INC., OF CHICAGO, ILLINOIS, A CORPORATION OF DELAWARE

HAND BRAKE

Application filed October 7, 1929. Serial No. 397,781.

This invention relates to improvements in hand brakes.

One object of the invention is to provide an efficient ratchet hand brake of the vertical staff type, for railway cars, of simple construction, wherein the parts are so designed as to avoid unnecessary weight without sacrificing strength.

Another object of the invention is to provide, in a brake of the character indicated, including a ratchet member and cooperating locking dog, a supporting housing and a fulcrum housing having an operating ratchet lever connected thereto, simple and efficient means in the form of a single retaining and locking element for holding all of the parts assembled, the locking element being so designed as to serve also as the pivot member for the locking dog of the brakes.

A still further object of the invention is to provide a ratchet hand brake of the vertical staff type including a locking dog and cooperating ratchet means, wherein means is provided for housing the dog and cooperating ratchet means and protecting the same from dust, dirt and other foreign material to prevent clogging of the parts, which would interfere with the efficient operation of the brake mechanism.

Other objects of the invention will more clearly appear from the description and claims hereinafter following.

In the drawing forming a part of this specification, Figure 1 is a vertical sectional view through the end wall of a railway car, showing my improved hand brake mechanism in connection therewith. Figure 2 is a top plan view of the brake mechanism illustrated in Figure 1, the end wall of the car being shown in section. And Figure 3 is a vertical sectional view, partly broken away, corresponding substantially to the line 3—3 of Figure 1.

In said drawing, the end wall of the car is designated by 10 and has the improved brake mechanism fixed thereto. My improvements are employed in connection with a ratchet hand brake of the vertical staff type, the upper portion of the staff being indicated by 11. As will be understood, the lower end 50 of the staff, which is not shown, has the usual

brake chain connected thereto, the same being adapted to be wound thereon in order to apply the brakes.

My improved construction comprises, broadly, a combined support and housing member A; a fulcrum housing B; a combined bearing and cover plate C; a brake staff D; a ratchet member E; an operating lever F; a locking dog G and a combined retaining member and locking dog pivot H.

The housing and supporting member A is in the form of a casting having a vertical wall section 12 which is secured to the end wall 10 of the car, rivets being preferably employed for fastening the same. The housing proper of the casting A comprises top and bottom walls 13 and 14, which are spaced apart as shown, and a vertical wall 15 connecting the top and bottom walls. As most clearly shown in Figures 1 and 2, the wall 15 comprises a cylindrical portion 16 and spaced side wall sections 17—17. The bottom wall 14 is provided with a journal opening 18, which is reinforced by a depending annular flange section. The top wall 13 of the housing A is 75 also provided with a journal opening 19 which is concentric with the opening 18 but of slightly greater diameter. The opening 19 is also reinforced by an upstanding annular flange 20.

The fulcrum housing B is also in the form of a casting and has a partly cylindrical portion 21 and a lateral extension 22 having side walls 23—23 and a top wall 24. The top wall 24, at the cylindrical section of the housing, is thickened as clearly shown in Figure 1 and provided with an interior journal pocket 25 adapted to cooperate with the upper end of the ratchet member E, as herein-after pointed out. The operating handle or lever F of the brake is of well known form and has the upper end thereof pivotally mounted within the housing B between the side walls 23—23 thereof. In the drawing, the upper end portion of the operating lever only is shown, it being understood that the same is provided with the usual hand grip portion at the outer end thereof by which the same may be manipulated. The inner end of the member F is provided with a 100

5 pocket 26 within which a sliding pawl 27 is mounted. The lever F is pivotally supported on a bolt 28 extending transversely through the lever and the side walls 23—23 of the housing B. The pivot bolt 28 also 10 serves as a limiting stop for the pawl, said bolt being accommodated within the cut away portion 29 of the pawl and adapted to engage the inner end wall of the cut away portion when the pawl is projected to its 15 full extent. A spring 30 is interposed between the inner end of the pocket 26 and the pawl 27, the pawl being recessed as indicated at 31, to accommodate the front end 20 of the spring. As most clearly illustrated in Figure 1, the top wall of the housing B is provided with a depending flange-like section 32, which forms a relatively short end wall connecting the side walls 23—23. As 25 will be evident, the depending wall section 32 provides a shield preventing dust and dirt entering the housing. The cylindrical portion 16 of the housing B is provided with a thickened section 33 at the bottom thereof, which section is offset with respect to the 30 cylindrical wall, so as to provide an arcuate retaining shoulder 34. The side walls of the housing B are connected at the bottom by a transverse web portion 35, which is substantially in alignment with the thickened bottom portion or section 33 of the cylindrical section of the housing. The housing B is 35 journaled for rotary movement on the supporting housing A, the former being provided with a depending annular flange 36 within 40 which the upstanding flange 20 of the housing A is telescoped.

45 The ratchet member E is in the form of a casting having a vertical opening of substantially square cross section, within which the upper end portion of the brake staff D extends. The upper end section of the brake staff, as shown, is of square cross section also, so as to fit the opening of the ratchet member, 50 whereby the staff and ratchet member are rotatable in unison. The ratchet member is provided with two sets of ratchet teeth 37 and 38, the teeth 37 cooperating with the pawl 27 of the operating lever F in a well known manner, so as to effect rotation of 55 the brake staff D when the lever F is oscillated while being disposed in a horizontal position. Between the two sets of ratchet teeth 37 and 38, the member E has a cylindrical journal portion 39 fitting the journal opening 19 of the housing A. At the bottom end, 60 below the ratchet teeth 38, the member E has a cylindrical bearing section 40 of smaller diameter than the journal portion 39, journaled in the opening 18 of the housing A. At 65 the upper end the ratchet member E is provided with a cylindrical journal portion 41 which rotatably fits the pocket 25 of the housing B.

70 66 The locking dog G comprises an operating

75 handle portion 42, offset with respect to the main body portion, and a tooth section 43 at the inner end thereof adapted to cooperate with the ratchet teeth 38 in order to prevent retrograde movement or rotation of the 80 brake staff D. The tooth 43 of the dog is urged yieldingly into engagement with the ratchet member 38 by the spring 44 interposed between the vertical end wall of the supporting housing A and the inner side of 85 the locking dog G. The locking dog is pivotally supported within the housing A by means of the combined retaining member and locking dog pivot H, as hereinafter pointed out.

90 The combined bearing and cover plate C is in the form of a casting having a straight transverse end face 45 adapted to bear on the upstanding portion of the vertical end wall 12 of the casting A. At the opposite side, the combined bearing and cover plate C is provided with an upstanding arcuate wall 46 adapted to fit about the cylindrical section of the casting B and forming a bearing and guiding seat therefor. The casting C is 95 cut away inwardly, beneath the wall 46, thereby providing an arcuate shoulder 47, which overlaps the shoulder 34 of the housing B. As will be evident, the combined bearing and cover plate thus serves to hold the housing B assembled with the housing A. The combined bearing and cover plate is detachably secured to the housing A, by means of the bolt H, which has the head thereof disposed in a pocket 48 provided in the member C. The bolt extends through the top and bottom walls of the housing A and is held in fixed position by a nut at the bottom end thereof engaging the bottom side of said housing. The bolt H also extends through the locking 100 dog G and serves as the pivot member for the same. As most clearly shown in Figure 1, the shank of the pivot bolt is enclosed by a cylindrical or tubular sleeve member 49 which protects the bolt against wear due to 105 the pivotal swinging movement of the locking dog. As shown, the top and bottom ends of the sleeve 49 are preferably fitted within the openings in the top and bottom walls of the housing B, through which the pivot bolt 110 passes.

115 In the operation of my improved hand brake mechanism, when it is desired to apply the brakes, the operating handle F is raised to horizontal position, so as to engage the pawl thereof with the tooth 37 of the ratchet member. Upon oscillation of the handle F in a horizontal path, intermittent rotation of the ratchet member will be effected, thereby causing rotation of the staff D and tightening of the brake chain. As will be obvious, during the oscillation of the operating lever F, the fulcrum housing B will be rotated or oscillated about the brake staff on the supporting housing A. The dog G which is 120 125

yieldingly urged into engagement with the ratchet member 38, prevents backward or retrograde movement of the brake staff. When it is desired to release the brakes, after the 5 lever F has been dropped so as to assume the vertical position shown in Figure 1, the handle of the dog is pulled outwardly, thereby disengaging the tooth 43 thereof from the ratchet member and permitting the brake staff to freely rotate in a direction to unwind the brake chain therefrom.

As will be evident from the preceding description, taken in connection with the drawing, I have provided a very simple and efficient means for holding the parts of the brake mechanism assembled, comprising the retaining element which also forms the pivot for the locking dog. By this means, the locking dog is held in assembled relation with the 10 supporting housing and through the medium of the combined bearing and cover plate C, the locking bolt or element also holds the fulcrum housing assembled with the supporting housing. As will be obvious, the upper 15 end of the brake staff and the ratchet member carried thereby is held in assembled position by engagement of the fulcrum housing therewith.

From the preceding description taken in 20 connection with the drawing, it will be seen that the members A and B together constitute a complete housing both at the top, bottom and around all sides, for the ratchet member E and parts immediately operatively associated therewith and further that, even though the member B is necessarily movable with respect to the member A, entrance of dirt or other foreign matter through the joint between these members is prevented by reason of the telescoping flange 36. By reason 25 of the construction disclosed, particularly with reference to the protection against entrance of dirt and other foreign matter, the improved brake is especially adaptable for use on ore cars and other cars employed for the carrying of coal and like granular and dusty material. Further, the improved housing arrangement will be found to be of materially less weight than other brakes of corresponding type which further adds to the advantages of my brake in the matter of cost of manufacture.

I have herein shown and described what I now consider the preferred manner of carrying out my invention, but the same is merely illustrative and I contemplate all changes and modifications that come within the scope of the claims appended hereto.

I claim:

60 1. In a hand brake of the vertical staff type, for railway cars, the combination with a rotary staff; of ratchet means on said staff; a supporting housing fixed to the car, said housing having journal openings in the top 65 and bottom thereof, journal members on said

staff rotatably supported in said openings; a fulcrum housing rotatably mounted on the supporting housing, said fulcrum housing having a depending annular flange telescoped over an upstanding bearing flange on the supporting housing, said fulcrum housing also having an arcuate shoulder concentric with said depending flange; an operating lever extending into the fulcrum housing and pivotally connected thereto for swinging movement in a vertical plane; means on said lever adapted to engage the ratchet means of the staff to effect rotation of the latter; and a combined locking and bearing plate detachably secured to the supporting housing, said plate having an arcuate bearing portion adapted to cooperate with the fulcrum housing and an arcuate shoulder engaging over the arcuate shoulder of the fulcrum housing to hold the same assembled with the supporting housing. 70 75 80 85

2. In a hand brake of the vertical staff type, for railway cars, the combination with a rotary staff; of ratchet means on said staff; a supporting housing fixed to the car, said housing having journal openings in the top 90 and bottom thereof, said staff having journal members thereon rotatably supported in said openings; a locking dog pivoted within the supporting housing and cooperating with the staff to prevent retrograde movement of the same; a fulcrum housing rotatably mounted on the supporting housing, said fulcrum housing having a depending annular flange telescoped over an upstanding bearing flange on the supporting housing, said fulcrum housing also having an arcuate shoulder concentric with said depending flange, an operating lever extending into the fulcrum housing and pivotally connected thereto; means on said lever adapted to engage the ratchet means of the staff to effect rotation of the latter; a combined locking and bearing plate detachably secured to the supporting housing, said plate having an arcuate bearing portion adapted to cooperate with the fulcrum housing and an arcuate shoulder engaging over the arcuate shoulder of the fulcrum housing to hold the same assembled with the supporting housing; a pivot bolt extending through the dog, said bolt being anchored to the supporting housing 100 and combined locking and bearing plate to detachably secure the latter to the supporting housing; and cooperating means on the supporting housing and combined locking and bearing plate to prevent turning of said plate 105 on the pivot bolt. 110 115 120

In witness that I claim the foregoing I have hereunto subscribed my name this 5th day of October 1929.

ROLAND J. OLANDER.
